US00D749323S

(12) **United States Design Patent**
Stahl

(10) **Patent No.:** **US D749,323 S**
(45) **Date of Patent:** **** Feb. 16, 2016**

(54) **BEVERAGE CRATE**

(71) Applicant: **Orbis Corporation**, Oconomowoc, WI (US)

(72) Inventor: **Edward L. Stahl**, Tyler, TX (US)

(73) Assignee: **ORBIS Corporation**, Oconomowoc, WI (US)

(**) Term: **14 Years**

(21) Appl. No.: **29/508,680**

(22) Filed: **Nov. 10, 2014**

(51) **LOC (10) Cl.** **03-01**

(52) **U.S. Cl.**

USPC **D3/308**

(58) **Field of Classification Search**

(57) **CLAIM**

I claim the ornamental design for a beverage crate, as shown and described.

DESCRIPTION

FIG. 1 is a perspective view of an embodiment of the ornamental design of a beverage crate;

FIG. 2 is a side plan view of a first side of the ornamental design of the beverage crate of FIG. 1;

FIG. 3 is an end plan view of a first end of the ornamental design of the beverage crate of FIG. 1;

FIG. 4 is a side plan view of a second side of the ornamental design of the beverage crate of FIG. 1;

FIG. 5 is a top plan view of the ornamental design of the beverage crate of FIG. 1;

FIG. 6 is an end plan view of a second end of the ornamental design of the beverage crate of FIG. 1; and,

FIG. 7 is a bottom plan view of the ornamental design of the beverage crate of FIG. 1.

Features shown in broken lines in the drawings (if any) are not part of the claim.

1 Claim, 7 Drawing Sheets
